DESIGN FOR AN INFANT'S SLEEPING BAG OR SIMILAR ARTICLE

Ruth J. McCarter and William H. McCarter,
Hanover, N. H.

Application June 8, 1935, Serial No. 57,204

Term of patent 7 years

To all whom it may concern:

Be it known that we, Ruth J. McCarter and William H. McCarter, both citizens of the United States and residents of Hanover, in the county of Grafton, State of New Hampshire, have invented a new, original, and ornamental Design for an Infant's Sleeping Bag or Similar Article, of which the following is a specification, reference being had to the accompanying drawing, forming a part thereof.

In the drawing,

sleeping bag having the features of our design incorporated therein, and

Figure 2 is a rear elevation of the infant's sleeping bag shown in Figure 1.

We claim:

The ornamental design for an infant's sleeping bag or similar article, as shown.

In witness whereof, we have signed our names to this specification this twenty-eighth day of May, 1935.

RUTH J. McCARTER.
WILLIAM H. McCARTER.
